(57) **CLAIM**

The ornamental design for a flow cell for a flow meter, as shown and described.

DESCRIPTION

FIG. 1 is a right side and top perspective view thereof;
FIG. 2 is a left side and bottom perspective view thereof;
FIG. 3 is a right side elevational view thereof;
FIG. 4 is a left side elevational view thereof;
FIG. 5 is a left end elevational view thereof;
FIG. 6 is a right end elevational view thereof;
FIG. 7 is a bottom view thereof; and,
FIG. 8 is a top view of the flow cell for a flow meter of FIG. 1. Broken lines are shown herein for illustrative purposes only, and form no part of the claimed design.
